ASSEMBLING ELEVATOR LIFT MECHANISM

Frederick N. McClintock, Jr., Havre de Grace, Md.

Application December 30, 1948, Serial No. 68,325

6 Claims. (Cl. 199—31)

1

My invention relates to improvements in power lift mechanism for the assembling elevators of typographical machines such as the "Linotype" and "Intertype" machines of commerce.

The primary object of my invention is to provide in such machines for lifting the assembling elevator by power under key control to obviate operation of the usual manually operative assembling elevator lifting means of these machines and thereby save time and labor, all by means of easily controlled mechanism of simple form and inexpensive construction adapted to be readily attached to such machines without altering the basic structure of the machines.

Another object is to provide a mechanism of the character and for the purpose above set forth which is powered by a spring and cocked for lifting operation by retraction of the line delivery lever of such machines, whereby a more simple and quickly acting power lift mechanism is provided for lifting the assembling elevator than has heretofore been achieved.

Still another object is to provide in conjunction with the above for variably and selectively counterbalancing the assembling elevator according to the overall weight of the same with different numbers of matrices composing a line therein, so as to reduce the load on the power lift mechanism to a minimum notwithstanding the length of the line of matrices assembled in the assembling elevator.

Still another object is to provide a power lift mechanism for such assembling elevators which will require a minimum of servicing and will not get out of order under prolonged use.

Other and subordinate objects within the purview of my invention, together with the precise nature of my improvements will be readily understood when the succeeding description and claims are read with reference to the drawings accompanying and forming part of this specification.

In said drawings:

Figure 1 is a fragmentary view in front elevation of a "Linotype" machine equipped with my improved power lift mechanism in a preferred embodiment thereof and with the parts shown in normal position.

Figure 2 is a similar view showing the parts in the position assumed thereby when the assembling elevator is fully lifted, or elevated.

Figure 3 is another similar view illustrating the position of the parts when the assembling elevator has descended with the rocker plate in fully operated position and the transfer lever at the end of its forward stroke;

2

Figure 4 is a fragmentary view in edge elevation of the assembling elevator, parts of the power lift mechanism, and the transfer lever detached from the machine;

Figure 5 is a view in horizontal section taken on the line 5—5 of Figure 3 and showing the catch pin and the leaf spring therefor drawn to a larger scale and with said pin projected;

Figure 6 is a fragmentary view in side elevation illustrating parts of the means for variably counter-balancing the assembling elevator and drawn to a larger scale;

Figure 7 is a view in horizontal section taken on the line 7—7 of Figure 6;

Figure 8 is a view in perspective of said counter-balancing means.

Referring now to the drawings by numerals, my improved power lift mechanism has been shown therein for the purposes of illustrating a preferred practice of the invention as applied to the usual "Linotype" machine of the class exemplified in U. S. Letters Patent No. 436,532 granted to O. Mergenthaler, September 16, 1890, the machine being shown conventionally in said drawings as sufficient for the present purposes.

In these machines matrices, not shown, are fed from a magazine, not shown, under control of keys 2 of the usual keyboard, to drop onto a belt 3 which delivers the matrices into an assembler 4 from which the same are fed by a star wheel (not shown) into the assembling elevator 5 in which the matrices are composed in a line with said elevator 5 in lowered normal position.

The assembling elevator 5, after the line is composed therein, is raised in guides 6, 7 to register the composed line of matrices with a horizontal channel 8 in a frame part 9 of the machine and position the line of matrices between a pair of line engaging fingers 10 on a transfer carriage 11 comprising a transfer slide 12.

The transfer carriage 11 is reciprocated by a vertical transfer lever 13 connected to the slide 12 of said carriage 11 by a link 14 and mounted on a rock shaft 15 of the machine, said lever having a forward and a reverse or retracting stroke to reciprocate said carriage 11. When the assembling elevator 5 is fully raised, or lifted, to elevate the composed line to the channel 8, it trips a catch, not shown, releasing the transfer carriage 11 which is then advanced by the forward stroke of the transfer lever 13 to transfer the composed line of matrices into the casting elevator 16 of the machine, after which said carriage 11 is retracted by the retracting stroke of said lever 13. A spring 17 operates said lever

13 through its forward stroke and cam means, not shown, subsequently retracts said lever 13. The assembling elevator is latched in elevated position until the transfer lever 13 executes its forward stroke and is then unlatched, by means, not shown, for descent into normal position under the influence of gravity.

The manually operative means of the machine for lifting the assembling elevator comprises a rock shaft 18 extending across the front of the keyboard or keys 2, and journaled at its ends through bearings 19 on the machine with an operating hand lever 20 at the right hand end of said shaft depressible to rock said shaft in a direction to cause the assembling elevator 5 to be lifted. A crank arm 21 and link 22 at the left hand end of said shaft 18 operatively connects said shaft to the assembling elevator 5. A coil spring 23 is connected to a crank arm 24 and to a fixed part 25 of the machine and serves the purpose of balancing the weight of the assembling elevator 5 in its lowered position and when unloaded.

My improved power lift mechanism comprises, as its basic element, a substantially semi-circular, segmental, rocker plate 26 journaled, as at 27, in a bearing 28 on the frame part 9 for vertical rocking movement from a normal position into a fully operated position in which said assembling elevator 5 is fully lifted, or elevated. The rocker plate 26 is arranged above the assembling elevator 5 behind the same and in front of the transfer lever 13.

The rocker plate 26 is powered for movement from normal position by a retractile coil spring 29 which is pivoted, as at 30, at one end to the frame part 9 and similarly connected at its other end, as at 31, to said plate 26 above the axis of said plate to rock the same in one direction from normal position into fully operated position.

A suitable stop pin 32 on the frame part 9 of the machine, in the path of movement of the rocker plate 26 from normal position is arranged to engage one edge of said plate and limits movement of the same to establish the fully operated position of said plate and, hence, the fully lifted or elevated position of the assembling elevator 5.

A radial peripheral shoulder 33 on said rocker plate 26 is engaged, in the normal position of said plate by a locking dog 34 whereby said plate is releasably held cocked in normal position in opposition to the spring 29. The locking dog 34 is pivoted, as at 35, on a suitable part of the machine and tensioned by a suitably arranged coil spring 36 to hook over said shoulder 33 with a snap action to lock said plate.

Operating connections are provided between the rocker plate 26 and the assembling elevator 5 in the form of a link 37 having a lower end pivoted, as at 38, to said elevator 5, and an arcuate concentric slot 39 in said plate having a leading end lateral notch 40, said link having an upper end lateral pin 41 slidable along said slot and into said notch 40. A coiled spring 42 having its ends fastened to said plate 26 and link 37, as at 43, 44, normally holds the pin 41 in the notch 40, in a manner presently clear, and over a catch lip 45 in said notch 40 so that when said plate 26 is operated from normal position, the link 37 and assembling elevator 5 will be lifted by said plate.

A knock off pin 46 on the bearing 28 is provided against which the upper end of the link 37 is swung by the rocker plate 26 as said plate nears

its fully operated position, whereby said pin 41 is knocked out of the notch 40 into the slot 39 for a purpose presently seen.

A key 47 at the left hand side of the keyboard, or keys, 2 is operatively connected by a rod 48 to the locking dog 34 so that, upon depression of said key, said dog 34 will be swung in opposition to the spring 36 to release the rocker plate 26 for operation by the spring 29.

Means are provided on the transfer lever 13 and the rocker plate 26 for moving said plate from fully operated position back to normal position by operation of said lever 13 during its retracting stroke. For this purpose, the transfer lever 13 is provided with a lateral, sliding catch pin 49 therein normally projected out of said lever by a leaf spring 50 on the lever bearing against a rear end head 51 on said pin adapted to engage said lever to establish a projected position of said pin. An arcuate, edge flange 52 on the rear face of the rocker plate 26 is provided for cooperation with the catch pin 49 and which, is interposed in the path of movement of a front cam end 53 of said pin 49, when said lever 13 executes its forward stroke. A camming edge 54 on said flange 52 is arranged for engagement with the cam end 53 of the catch pin 49 during the forward stroke of the transfer lever 13 so that pin 49 is retracted to wipe over and past the flange 52 as the transfer lever 13 executes its forward stroke. As the catch pin 49 wipes past the flange 52 it is projected by the leaf spring 50 so as to engage and pick up said plate 26 during the retracting stroke of the said lever, for a purpose presently seen.

The means for variably counter-balancing the assembling elevator 5 comprises the following devices. The hand lever 20 is fast at one end on a bushing 55 which is pivotally and slidably mounted on one end of the rock shaft 18 in one bearing 19 for vertical rocking and endwise sliding movement on said shaft. The bushing 55 has the crank arm 24 formed thereon and the bushing end of said lever 20 is provided on one side of the lever with grooves 56 radial to the rock shaft 18. The rock shaft 18 is provided with a radial pin 57 for registration with and seating in said grooves 56, selectively, by swinging of the hand lever 20 on the rock shaft 18 and endwise sliding of the bushing 55 in a manner presently clear. An expansion coil spring 58 on the bushing 55 is interposed between the adjacent bearing 19 and the hand lever 20 and tends to slide said bushing 55 and hand lever 20 toward said pin 57 and thereby seat the pin 57 in a selected groove 56.

Referring now to the operation of the invention, with the parts in normal position, as shown in Figure 1, and when it is desired to lift the assembling elevator 5, the key 47 is depressed to swing the locking dog 34 into releasing position relative to the shoulder 33 and the rocker plate 26. This frees the rocker plate 26 for operation by the spring 29 from normal position into fully operated position against the stop pin 32 and as illustrated in Figures 2 and 3. During such operation of the rocker plate 26, since the pin 41 is seated in the notch 40, in the normal position of said plate 26, the link 37 is lifted to lift the assembling elevator 5 to fully lifted or elevated position. When the assembling elevator 5 reaches fully lifted, or elevated position, shown in Figures 2 and 3, and just before the rocker plate 26 engages the stop pin 32, the link

37 is brought into engagement with the knock off pin 46, whereby said link 37 is swung on its pivot 38 to move the pin 41 out of the notch 49 into the slot 39. At this point, the assembling elevator 5 is freed to descend to lower normal position, under the influence of gravity, when unlatched by the usual mechanism of the machine. During such descent of the assembling elevator 5, the pin 41 slides downwardly in the slot 39 of the rocker plate 26. The rocker plate 26, however, is held in fully operated position by the spring 29 until the transfer lever 13 executes its retracting stroke.

When the transfer lever 13 executes its forward stroke, the catch pin 49 wipes past and over the flange 52, in the manner already described. However, when the transfer lever 13 executes its retracting stroke, the cam end 53 of the catch pin 49 engages the rocker plate 26 above its pivotal axis and picks up the same and thereby rocks the rocker plate 26 to move the same back to normal position in which the locking dog 34 snaps over the shoulder 33 and locks said rocker plate 26 in normal cocked position for repeat operation. As the rocker plate 26 becomes locked, the catch pin 49 rides upwardly off the same because of the throw of said lever 13, and plate 26, and becomes disengaged from said plate. During movement of the rocker plate 26 to normal position, the pin 41 rides in the slot 39 into a position opposite the notch 49 and the spring 42 then swings the link 37 to seat the pin 41 in said notch to operatively connect said plate 26 to the assembling elevator 5 for repeat operation of said plate 26 to lift said elevator.

Prior to power lifting of the assembling elevator 5, the hand lever 20 may be slid away from the pin 57 along the rock shaft 18, in a manner which will be seen, free of said pin, and then be swung upwardly to variably stretch the spring 23 according to the weight of the assembling elevator 5 plus the weight of the line of matrices therein. Then said lever 20 may be locked to the rock shaft 18 by permitting it to slide toward the pin 57, under the action of the spring 58, until a selected groove 56 seats the pin 57 therein. Thus, the spring 23 may be variably stretched to variably tension the rock shaft 18 against being rocked through the medium of the crank arm 21 and link 22 during lifting of the assembling elevator 5 by the power lift mechanism, whereby the assembling elevator may be variably counterbalanced according to the weight of the same plus the weight of the matrices assembled therein.

The foregoing will, it is believed, suffice to impart a clear understanding of my invention, without further explanation.

Manifestly, the invention, as described, is susceptible of modifications, without departing from the inventive concept, and right is herein reserved to such modifications as fall within the scope of the appended claims.

Having described the invention, what is claimed as new is:

1. In a machine of the class described, a matrix assembling elevator, a key, power lift means for said elevator comprising a plate pivoted above said elevator for vertical rocking movement into and from a normal position and power operated from normal position under control of said key, spring operated means connecting said elevator to said plate in the normal position of said plate to lift said elevator by movement of said plate

from normal position and operative to disconnect said elevator from said plate, means operating said spring operated means to disconnect said elevator from said plate after said elevator has been lifted, and power operated means engaging said plate to move the same into normal position after said elevator is disconnected from said plate.

2. The combination of claim 1 wherein said last named means includes a pivoted lever having a member thereon wipingly engaging one edge of said plate.

3. In a machine of the class described, a matrix assembling elevator, a key, a plate having a slot therein with a lateral end notch, means pivotally mounting said plate above said elevator for vertical rocking movement from and into a normal position to raise and lower said slot and notch, a member pivoted to said elevator and having a pin traversing said slot and slideable downwardly therein when said slot and notch are raised, spring means biasing said member to move said pin into said notch in the normal position of said plate for lifting by said notch to raise said member and elevator by movement of the plate from normal position, power means for moving said plate from normal position under control of said key, and means moving said pin out of said notch and into said slot when said elevator is raised to slide downwardly in said slot under the weight of said member and elevator and provide for descent of said elevator, and means to move said plate into normal position after descent of the elevator.

4. The combination of claim 3 wherein said last named means comprises a pivoted power operated lever having means thereon wipingly engaging one edge of the plate.

5. The combination according to claim 3 wherein said slot is concentric to the axis of movement of said plate to provide for movement of said plate into normal position while said pin is in downwardly slid position.

6. In a machine of the class described, a matrix assembling elevator, a key, a plate having a slot therein with a lateral end notch, means pivotally mounting said plate above said elevator for vertical rocking movement from a normal position to raise said slot and notch, a member pivoted to said elevator and having a pin traversing said slot and slideable downwardly therein when said slot and notch are raised, spring means biasing said member to move said pin into said notch in the normal position of said plate for lifting by said notch to raise said member and elevator by movement of the plate from normal position, power means for moving said plate from normal position under control of said key, and means moving said pin out of said notch and into said slot when said elevator is raised to slide downwardly in said slot under the weight of said member and elevator and provide for descent of said elevator.

FREDERICK N. McCLINTOCK, JR.
